SUCTION CLEANER

Joseph L. Ray, New York, N. Y., assignor to The Singer Manufacturing Company, Elizabeth, N. J., a corporation of New Jersey

Application June 9, 1934, Serial No. 729,746

3 Claims. (Cl. 280—44)

This invention relates to suction cleaners of the type embodying a motor-driven suction-fan and fan-casing supported on wheels and having a forwardly extending suction mouth or nozzle and an upwardly and rearwardly extending handle whereby the machine may be propelled over the floor or floor-covering to be cleaned.

In floor cleaners of the type in question it is customary to provide for the raising and lowering of the suction-nozzle relative to the floor surface or covering to be operated upon, by the incorporation of means for vertically adjusting the axis of one or more of the supporting wheels relative to the frame or casing of the machine.

Floor coverings vary considerably in thickness and texture and, for the efficient cleaning thereof, it is desirable that the height of the suction-nozzle of the cleaner be adjusted to suit the particular floor covering being operated upon.

In moving the cleaner about from one floor covering to another, there may be need for adjustment of the nozzle height and unless this adjustment can be made quickly and conveniently, it is likely to be neglected, with a resulting loss of efficiency in the operation of the machine.

The present invention has for an object to provide means for adjusting the nozzle-height of a suction cleaner which may be so conveniently and quickly operated to secure any desired adjustment, as to materially reduce the likelihood of its being neglected by the user in the normal day-by-day use of the machine.

Another object of the invention is to so construct the device that any desired adjustment may be instantly made by a single and quickly executed movement of an adjusting knob or handle, without the necessity of prior or subsequent manual operation of clamping or holding devices for maintaining the adjustment against displacement while the cleaner is in use.

With the above and other objects in view, as will hereinafter appear, the invention comprises the devices, combinations, and arrangements of parts hereinafter set forth and illustrated in the accompanying drawings of a preferred embodiment of the invention, from which the several features of the invention and the advantages attained thereby will be readily understood by those skilled in the art.

In the accompanying drawings, Fig. 1 is a side elevation of a suction cleaner embodying the invention. Fig. 2 is a bottom plan view of the rearwardly disposed wheeled truck for supporting the cleaner. Fig. 3 is a section on the line 3—3, Fig. 1, on an enlarged scale. Figs. 4 and 5 are,

respectively, sections on the lines 4—4 and 5—5, Fig. 2. Fig. 6 is a sectional view through the adjusting device in a plane at right angles to the plane of the section shown in Fig. 3. Fig. 7 is a disassembled perspective view of the guide, screw and follower elements of the adjusting device. Fig. 8 is a disassembled perspective view of the handle and yielding detent elements of the device. Fig. 9 is a side elevation of the screw-element alone, and Fig. 10 is a disassembled perspective view of the bearing plate for the rearwardly disposed wheeled truck of the cleaner.

In the preferred embodiment of the invention illustrated there is a main body or frame 1 including a motor-driven suction-fan 2 and fan-casing 3 having a forwardly projecting and down-turned suction-nozzle or mouth 4. The main body 1 is supported in front by the forwardly disposed pair of wheels 5 and in rear by the pair of wheels 6. The usual propelling handle 7 is pivoted to the body 1 at 8 and a dust-bag 9 is connected to the dust-discharge outlet 10 of the suction-fan casing 3.

The forwardly disposed wheels 5 are journaled on independent but coaxial bearing studs 11 at 25 the under side of the body 1. The rearwardly disposed wheels 6 are journaled on a pivoted truck comprising the aligned and offset ends 12 carried by the crank-arms 12 of a pivot-shaft 13 which is journaled in the grooved bearing plate 14 30 screwed to the under side of the body 1. The aligned and offset ends 12 of the pivot-shaft 13 are parallel to the pivotal axis of such shaft and are off-set to the rear of such pivotal axis. The bearing plate 14 has in its shaft-receiving groove 35 15 a central pocket 16 in which is disposed a rubber block 17 which presses the shoe 18 against the shaft 13 with sufficient pressure to frictionally hold the shaft against turning in the bearing 40 plate when the cleaner is lifted from the floor for any reason.

Projecting from one side of the main body or frame 1, adjacent the dust-discharge outlet 10, is a vertically bored lug 19 in which is fixed 45 a cylindrical bushing 20 having the diametrically opposed vertical guide-slots 21 extending straightaway longitudinally of such bushing.

Rotatably mounted in the guide bushing 20 is the tubular screw-member 22 having a flange 50 23 at its lower end, a central hole 24, a reduced neck 25, and a pair of diametrically opposed screw-slots 26 extending spirally upwardly from the lower end of such screw-member and terminating in the end-stop walls 27. The screw-

slots 26 have a steep pitch which in the present instance is about 33°.

Slidably fitted in the hole 24 in the tubular screw-member 22 is a screw-follower rod 28 in which is fixed the screw-follower cross-pin 29 which extends laterally in opposite directions from the rod 28 through the spiral screw-slots 26 in the member 22 and has reduced terminal portions 30 on which are journaled anti-friction rollers 31 received in the guide-slots 21 in the bushing 20.

A manually operated adjusting handle 32 is fixedly secured to the reduced neck 25 of the screw-element 22. A spring-pressed detent in the form of a ball 33 is housed in the handle 32 and is urged downwardly by the spring 34 and pressure-head 35 upon the circular detent plate 36 having a circular series of detent holes 37 therein and a pair of downwardly struck positioning lugs 38 which enter positioning apertures 39, Figs. 3 and 7, in the upper end of the bushing 20.

It will be observed that the lower end of the follower rod 28 is rounded and bears upon one of the crank-arms 12' of the pivoted truck carrying the rear wheels 6. By a swiftly executed motion of the handle 32 the operator may instantly raise or lower the rear end of the body 1 relative to the axis of the rear wheels 6, thereby lowering or raising the nozzle 4 from the surface being operated upon. The motion of the handle 32 in a counter-clockwise direction to elevate the nozzle 4 is limited by engagement of the rollers 31 with the end-stop walls 27 of the screw-slots. The motion of the handle 32 in the reverse direction is limited by engagement with the frame casing adjacent the dust-discharge outlet 10. The extreme range of motion of the handle 32 covering the full range of adjustment of the nozzle 4, is less than one complete revolution; being in the present instance about 190°. Thus the desired adjustment may be very easily and quickly effected. Furthermore, by combining the spring-pressed detent 33, 36 with the steeply pitched screw 22, the adjustment is automatically held against displacement notwithstanding the tendency of the reverse or reactionary pressure of the rod 28 upon the screw 22 to turn the latter, yet the adjustment may

be instantly changed without the necessity of manipulating special adjustment holding nuts, screws or the like, prior and subsequent to the actual adjusting operation. A spring 40 is preferably disposed in the hole 24 in the screw-element 22 between the upper end of the rod 28 and the handle 32 to partially offset or counter-balance the upward thrust on the rod 28 by the underlying crank-arm 12' of the pivoted truck.

Having thus set forth the nature of the invention, what I claim herein is:—

1. An adjusting device for a vacuum cleaner support comprising, a main body, a bushing fixed in said main body and having a guide-slot extending longitudinally thereof, a spirally slotted tubular adjusting screw journaled in said bushing, a screw follower rod slidable longitudinally of and within said tubular screw, and a screw-follower projecting laterally from said rod through the spiral slot in said tubular screw and into the longitudinal guide-slot in said bushing, said follower rod being adapted to sustain the upward thrust of a vacuum cleaner support.

2. An adjusting device for a vacuum cleaner support comprising, a main body, a cylindrical bushing fixed in said main body and having a pair of diametrically opposed guide-slots therein extending straightaway longitudinally thereof, a tubular member journaled in said bushing and having a pair of diametrically opposed screw-slots therein extending spirally longitudinally thereof, and a follower rod slidable longitudinally of and within said tubular member, a cross-pin fixed in said rod and extending through said screw-slots and into said guide-slots, said follower rod being adapted to sustain the upward thrust of a vacuum cleaner support.

3. An adjusting device for a vacuum cleaner support comprising a body having a cylindrical bearing aperture and a guideway in the wall of such aperture, a spirally slotted tubular adjusting screw journaled in said aperture, a screw follower rod slidable longitudinally of and within said tubular screw, and a screw-follower projecting laterally from said follower-rod through said screw and into said guideway, said follower-rod being adapted to sustain the upward thrust of a vacuum cleaner support.
